UNITED STATES PATENT OFFICE.

RALPH BAGALEY, OF PITTSBURG, PENNSYLVANIA.

CRANE.

SPECIFICATION forming part of Letters Patent No. 369,423, dated September 6, 1887.

Application filed May 2, 1887. Serial No. 236,759. (No model.)

To all whom it may concern:

Be it known that I, RALPH BAGALEY, residing at Pittsburg, in the county of Allegheny and State of Pennsylvania, a citizen of the United States, have invented or discovered certain new and useful Improvements in Cranes, of which improvements the following is a specification.

In the accompanying drawings, which make part of this specification, Figure 1 is a view in side elevation of a hydraulic crane embodying my invention. Fig. 2 is a top plan view of the same. Fig. 3 is a sectional view on the line *x x*, Fig. 1. Fig. 4 is a view similar to Fig. 3 of a modified construction.

The invention herein relates to certain improvements in hydraulic and other cranes, and has for its object such a construction and combination of parts as will permit of the free movement of the jib both vertically and horizontally independent of the mast or standard and of a free inward or outward movement of the load without subjecting the mast or standard to lateral thrusts or strains.

The lower end of the mast or standard 1 is arranged in the hydraulic cylinder 2 in the usual manner, and in the upper end of the mast is formed a socket, 3, for the reception of the pivot-pin of the head 4. This head is formed with prongs 5, between which is arranged the jib 6, pivotally supported midway of its length by the pin 7, passing through the prongs. On the upper edge of the jib is formed a rib, 8, serving as a track or guide for the grooved rollers 9, having axles 10, from which depend the bridles or yokes 11. To the axles 10 are also attached the rods 12, preferably V-shaped in cross-section and provided with teeth on one of their sides, as shown. These rack-rods are made of sufficient length to extend from the outer ends of the jib to and beyond the head of the standard, where they engage a pinion, 13. This pinion 13 is secured to a short shaft, 14, journaled in the prongs 5 of the head, and is provided with grooved or sprocket wheel 15, over which passes a rope or chain, 16, whereby the pinion may be rotated. The rack-bars are held in engagement with the pinion by the friction-rollers 17, mounted on short shafts

journaled in the prongs of the head. To the bridle on one end of the jib is attached the fork 18, or any other suitable device for holding the piece of work to be moved, and to the bridle at the other end of the jib is attached a chain, 19, or other device for supporting counterbalancing-weights 20.

In operating my improved crane, after the object to be moved has been placed on the fork 18, sufficient weights are attached to the chain 19 to counterbalance said object, or approximately so. The mast can then be raised or lowered, as required. Should it be necessary to move the object in or out along the jib, this can be effected by rotating the pinion 13, the counterbalancing-weights being simultaneously and equally moved, so as to preserve the equilibrium of the jib. Any small vertical movement of the object can be effected by causing the jib to rotate on its pivot-pin 7. The pin-and-socket connection between the mast and head 4 permits of a horizontal rotation of the jib.

In some instances it may be desirable, or even necessary, to use a single weight, the counterbalancing of the object to be lifted being effected by moving the weight 20 independently in or out along the jib. In such cases the head of the mast or standard is constructed as shown in Fig. 4—*i. e.*, with a transverse slot, in which the jib is pivoted, and with prongs 22 on the head above the jib. Between these prongs are arranged the operating-pinions 13, secured to independent shafts 14, provided with operating-wheels 15.

The above-described construction permits of the independent adjustment of the loads on opposite ends of the jib.

The above-described jib and its connections can be adapted for use with a stationary mast, and hence I do not limit myself to the combination with a vertically-movable mast or standard.

I claim herein as my invention—

1. In a crane, the combination of a vertical post or standard, a centrally-pivoted jib, and suspending devices mounted on the jib on each side of its pivotal point and movable therewith, substantially as set forth.

2. In a crane, the combination of a vertical

post or standard, a jib centrally pivoted on said standard so as to permit of vertical and horizontal movement thereof, and suspending devices mounted on the jib on each side of its pivotal point and movable therealong, substantially as set forth.

3. In a crane, the combination of a vertical post or standard, a centrally-pivoted jib, and suspending devices mounted on the jib on each

side of its pivotal point, and means for simultaneously moving them in opposite directions, substantially as set forth.

In testimony whereof I have hereunto set my hand.

RALPH BAGALEY.
